United States Patent Office.

H. K. SEARS AND S. L. HOLT, OF HARTFORD, CONNECTICUT.

Letters Patent No. 65,126, dated May 28, 1867.

IMPROVEMENT IN OIL-CUPS.

The Schedule referred to in these Letters Patent and making part of the same.

TO ALL WHOM IT MAY CONCERN.

Be it known that we, H. K. SEARS and S. L. HOLT, of Hartford, county of Hartford, and State of Connecticut, have invented certain new and useful Improvements in "Oiler" Cans; and to enable others skilled in the art to make and use the same, we will proceed to describe by referring to the drawings, in which the same letters indicate like parts in each of the figures.

The nature of this invention consists in the peculiar mode of closing the drip or air-orifice in oil-cans at the point of time when the oil or other lubricating fluid is about to be ejected from the can through its nozzle, by pressure upon the bottom of the can, so as to allow any drip remaining upon the outside of the nozzle to return back into the can through an orifice provided expressly therefor.

In the accompanying drawings is shown a section view of an "oiler" can as now made and in common use, with this exception, that we have formed an orifice, *a*, through the stopper, and inserted (from the inside) a small tube, *c*, into said orifice or stopper, through which the drip, which may at any time remain upon the outside of the nozzle, may return into the can. *d* is a weight-valve, arranged upon a wire rod, *e*, which extends downward to the bottom of the can, and sustained in its proper position by means of a guide and supporting-arm, *i*. This valve-rod is designed to be of such length that when pressure is applied to the bottom it will close the valve, against the tube *c* just at that point of time when the fluid is ejected from the can through the nozzle in the usual way, thus preventing the fluid from being ejected through the tube or orifice *a*, and allowing any drip which may remain on the outside of the nozzle to return through the orifice *a* into the can. This valve-rod also serves to prevent the set of the bottom of the can.

"Oilers" have been heretofore made without any cheap, simple arrangement for taking up the drip, and for want of which the cans have become besmeared with fluid, and thereby very annoying to handle, which, by the use of this improvement, is entirely obviated. In this way we are enabled to produce a cheap and useful article of manufacture and use.

We believe we have thus shown the nature, construction, and advantage of this improvement so as to enable others skilled to make and use the same therefrom.

What we claim as our invention, and desire to secure by Letters Patent, is—

The combination of the passage *a*, valve *d*, guide *i*, and rod *e*, all arranged to operate substantially as and for the purpose described.

H. K. SEARS. [L. S.]
S. L. HOLT. [L. S.]
